UNITED STATES PATENT OFFICE.

ERNEST J. CROCKETT, OF LOS ANGELES, CALIFORNIA, ASSIGNOR, BY MESNE ASSIGNMENTS, OF ONE-HALF TO A. M. YOUNG AND ONE-HALF TO G. JOHNSON RITTENHOUSE, BOTH OF LOS ANGELES, CALIFORNIA.

RECEPTACLE-MAKING MACHINE.

1,266,772.

Specification of Letters Patent.

Patented May 21, 1918.

Application filed April 5, 1915, Serial No. 19,112. Renewed January 29, 1918. Serial No. 214,417.

To all whom it may concern:

Be it known that I, ERNEST J. CROCKETT, a citizen of the United States, residing at Los Angeles, in the county of Los Angeles 5 and State of California, have invented a new and useful Receptacle-Making Machine, of which the following is a specification.

An important object of this invention is the provision of a machine for producing a 10 receptacle that is inexpensive and that will operate to effect great strength of the receptacle even though the strip material used by the machine in the manufacture of the receptacles may be in itself, previous to its 15 incorporation in the product, incapable of withstanding great strains.

Another object is the production of a machine that will so wind and arrange strip material such as paper or other fibrous material 20 as to produce receptacles of maximum strength and minimum liability to leak.

Another object is to so arrange strip material in layers as to produce maximum smoothness of the inside and outside surfaces of the receptacles.

Another object is to so wind strip material as to make the winding operation continuous.

Another object is to produce a machine 30 capable of manufacturing each receptacle in a minimum amount of time.

Other objects and advantages may appear from the subjoined detail description.

Figure 1 is a rear elevation of a machine 35 embodying the invention, and supplied with strip material.

Fig. 2 is a side elevation from line indicated by x^2-x^2 , Fig. 1 looking toward the right, portions of the core being broken 40 away for clearness of illustration and the strip material being omitted.

Fig. 3 is a broken plan view of Figs. 1 and 2, showing the core wrapping.

Fig. 4 is a longitudinal mid section of 45 the core, a fragment of the head-retaining arm also being shown.

Fig. 5 is an enlarged cross section of the core-body on line indicated by x^5-x^5 , Fig. 4.

Fig. 6 is an enlarged sectional detail on 50 line indicated by x^6-x^6 , Fig. 2.

Generally stated, there are provided means to wind strip material in layers of helical turns so that the turns in one of said layers diagonally cross the helical turns in another

of said layers, and the helical turns of alternate layers progress aslant toward one end of the receptacle and the helical turns of adjacent layers progress aslant toward the opposite end of the receptacle and adjacent layers overlie one another.

Spools 4, 5, 6 to hold cartridges or rolls of strip material such as paper or other fibrous material are mounted on suitable spindles 7 carried by a standard 8 of a bracket 9. The spools 4, 5, 6 are in staggered relation with one another and the strips 10, 11 from the lower spools 4, 5 are threaded over a guide or roller 12 mounted on the standard and the strip 13 from the upper spool 6 is threaded under said roller.

All of the strips 10, 11, 13 are threaded around a guide roller 14 mounted on the bracket 9 and over a roller 15 which is rotatably mounted on an adjusting arm 16 pivoted to a feeder head 17 swiveled on the upper flanged end of an oscillating feeder arm 18 which carries the bracket 9 said arm 16 being pivoted to a connecting rod 19 that in turn is pivoted to an operating lever 20.

The operating lever 20 is pivoted to said feeder head, so that movement of the lever 20 will raise and lower the roller 15 in order to alternately bring the strips 10, 11, 13 out of and into engagement with a distributing roller 21 rotatably mounted in a tank 22 designed to contain a binder such, for instance, as silicate of soda. Thus the binder is spread on the under surfaces of the strips 10, 11, 13 by the distributing roller 21, as the strips pass over said roller.

The strips 10, 11, 13 are threaded from the distributing roller 21 over a guide roller 23 rotatably mounted on the feeder head 17. The rollers 12, 14, 15, 23 may be provided with flanges 24 to prevent the edges of adjacent strips overlapping one another.

The feeder arm 18 is pivoted at its lower end at 25 to a suitable frame 26 and is pivoted intermediate its ends at 27 to one end of an actuating rod 28 which is provided at its opposite end with a pivot 29 engaging a slot 30 in the lower end of a lever 31.

The lever 31 is fulcrumed intermediately at 32 to the frame 26 and is provided at its upper end with a slot 33, see Fig. 6, engaged by a stud 34 which projects from a collar 35 reciprocably mounted on a cam shaft 36 having a cam track in the form of reversely

directed helical grooves 37, 38 and end grooves 39 connecting the ends of the groove 37 to the ends of the groove 38, each of the grooves 39 being approximately one-half of a straight turn.

5 The grooves 37, 38, 39 accommodate a crescent shaped follower 40, see Fig. 6, having a stud 41 projecting into a seat 42 located in the collar 35, said seat extending 10 up through a boss 43 that is externally threaded to receive a cap 44 into which is screw threaded a lubricating cup 45.

The cam shaft 36 rotates in bearings 46, 47 of the frame 26 and is provided on its 15 outer end with a sprocket wheel 48 engaging a sprocket chain 49 which is driven by a sprocket wheel 50 mounted on the outer end of a shaft 51 journaled at 52, 53 on the frame, said shaft being provided with fast 20 and loose pulleys 54, 55 to receive a driving belt, not shown, which thus drives the shaft 51 when said belt engages the fast pulley 54 and which can be shifted by the usual means, not shown, from said fast pulley to the loose pulley 55 when it is not desired to 25 operate the machine.

The shaft 51 turns a collapsible core of suitable construction and in the instance shown, said core comprises heads 56, 57 and 30 an intermediate barrel shaped core-body formed of longitudinally curved segments 58, 59 which are pivoted at 60, 61 to arms 62, 63 respectively that are pivoted at 64 to hubs 65 fastened by keys 66 or the like to the 35 shaft 51, said arms 63 being sectional and provided with knuckle joints 67. The arms 63 are provided at their knuckle joints with complementary beveled ends 68 so that said arms can fold only toward the head 57.

40 The shaft 51 is provided with a conical centering end 69, and the head 56 is provided with a hub 70 fastened by a key 71 or the like to the shaft 51, and the head 57 is provided with a centering pin 72 fastened 45 to said head by a key 73 or the like, said centering pin having a conical centering end 74 designed to be in alinement with the centering end 69 of the shaft when the head 57 is in place.

50 The centering pin 72 is provided with a conical centering socket 75 to receive the conical end of a pivot 76 which is mounted in one end of a swinging arm 77, that is pivoted at the other end at 78 to a bracket 55 79 of the frame 26, said swinging arm 77 being yieldingly held toward the head 57 to hold said head in place by a coil spring 80 fastened at its opposite ends to the swinging arm 77 and frame 26.

60 The head 56 is provided in its outer face with a slot 81 to receive one end of a spring clip 82 having its other end bent over the periphery of said head to hold the ends of the strips 10, 11, 13 as in Fig. 3.

65 The upper end of the feed arm 18 is pro-

vided with a socket 83 to receive the pivot 84 of the head 17 and is provided with stops 85, 86 projecting up into the path of the head, said stops being spaced apart so as to allow the head to swing at different angles 70 and said stops limiting the angular movement of the head. The stops 85, 86 are so positioned relative to the head 17 that when the head engages said stops the head will be at the correct angle to allow the 75 strips 10, 11, 13 to pass from the roller 23 at angles substantially coinciding with the pitch or angle of progression of the helical turns a, b of the strips.

I have provided means for alternatively 80 turning the head 17 first at an angle coinciding with the angle of progression of the helical turns a and then at an angle coinciding with the angle of progression of the helical turns b , and said means are constructed 85 as follows:

The head 17 is provided with downwardly projecting lugs 87, 88 forming stops designed to engage stops 89, 90 respectively in the form of collars fixed by set screws 91 to 90 a rod 92 which passes through the lugs and is fastened by nuts 93 to a bracket 94 of the frame 26.

The collars 89, 90 are fastened at such positions on the rod 92 as to engage the lugs 95 87, 88 respectively. When the follower 40 is near the ends of the respective cam grooves 37, 38 so that when the follower passes into the grooves 39 the head will have been turned sufficiently to engage the stops 100 85, 86 respectively.

The core segments 58, 59 are provided at their ends adjacent the head 57 with points 95 projecting toward the inner face of the head 57 for the reason hereinafter set forth. 105

In practice the tank 22 will be provided by the attendant with a suitable substance such as silicate of soda or the like, and the spindles 7 will be supplied with spools of strip material such as paper or other suitable fibrous substance and the strips 10, 11, 13 will be threaded to engage the guide rollers 12, 14, 15 and 23. The lever 20 will be operated to raise the roller 15, thus to hold the strips 10, 11, 13 free from the distributing roller 21. A permanent head 96 of wood or other suitable material having centering sockets 97 will then be placed at the forward end of the core between the core-body and the head 57 and forced against the points 95 to embed said points in the permanent head, see Fig. 4, said points holding the permanent head against rotation relative to the core. 115

Assuming at the start that the feed arm 18 is in such position that the roller 23 is directly over the head 56, the free ends of the strips 10, 11, 13 will be fastened under the spring clip 82 and the machine will then be started into operation by turning the driv- 125 130

ing pulley 54 by a power driven belt, not shown, so as to turn the core in the direction of the large feathered arrow 98, Fig. 1, to wind the strips with abutting edges in helical turns *a* progressing toward the head 57 to form an inner layer *c*. When the cam shaft 36 has rotated sufficiently to swing the feed arm 18 far enough so that the feed head 17 is adjacent the head 57 the layer *c* is completed, and the collar 90 will engage the lug 88 and turn the head 57 against the stop 86.

Then the lever 20 will be operated to lower the roller 15 to allow the strips 10, 11, 13 to contact with the distributing roller 21 and said cam shaft 36 reverses the movement of the feed arm 18 so as to wind the strips in a reverse direction in helical turns *b* overlapping the turns *c* in the first layer and diagonally crossing the turns of the first layer, thus forming a second coated layer *d* bound by the silicate of soda to the first layer. At the end of this movement the collar 89 engages the lug 87 and turns the head 17 preparatory to winding a third layer.

Thus the feed arm 18 is caused to swing to and fro to wind the strip material to and fro around the core as the core revolves and the winding operation is continued until any desired number of layers have been wrapped on the core to form a tubular body, there being two or more layers according to the use to which the receptacle is to be put.

When the desired number of layers have been formed, the operator will sever the unwound portions of the strips 10, 11, 13 from the wound portions thereof and trim off sufficient of the wound strips at the head 57 to free said head from being held by the strips and he will then swing the arm 77 away from the head 57 and remove said head. Then he will grasp the arms 63 and bend the same at the knuckle joints 67 to cause the segments 59 to be drawn radially inward toward the shaft 51. The operator will then grasp the tubular body and pull the same forward together with the permanent head 96 away from the head 56, thus causing the arms 62 to swing forward and the segments 58 to collapse inward along- side of the segments 59 so as to free the tubular body from the core.

The strips 10, 11, 13 will then be trimmed off by hand or otherwise and the receptacle may be finished off in any suitable manner, as, for instance, disclosed in my co-pending application for receptacle, filed March 17, 1915, Serial No. 14,913.

The process or method outlined above is not claimed herein but is the subject of my co-pending application for method of making receptacles, filed March 30, 1915, Serial No. 18,002.

The pivot 25 is so located relative to the roller 23 that when the arm 18 swings said roller will move in a curve corresponding to

the curvature of the segments 58, 59, and it is understood that said roller 23 may be swung in an arc by any suitable means and that I do not limit the scope of the invention to the exact construction shown in the drawings for effecting such result.

The swinging of the roller 23 in a curved path and also so that the axis of said roller is normal to the angle of progression of the helical turns produces maximum smoothness and tightness of the turns.

What I claim is:

1. A receptacle making machine comprising a collapsible core-body, having longitudinally curved segments, means operating in an arc to wrap a strip of material around said core, and means to cause said wrapping means to operate in a curve corresponding to the curve of the segments.

2. A receptacle making machine comprising a collapsible core body, a head, a spring-pressed arm holding said head toward said core body, and means to wrap a strip of material around said head and core body.

3. A receptacle making machine comprising a collapsible core body, a head at one end of said core body, a centering pin in said head, a swinging arm provided with a pivot to engage said centering pin, means to turn the core body, and means to feed strip material along the core body and head while said core body is turning.

4. A receptacle making machine comprising a shaft, a collapsible core body mounted on said shaft, a head mounted on the shaft at one end of the core body, a second head, a swinging arm to hold the second head toward the core body, means to turn the shaft, and means to feed strip material along the core body and heads while the core is turning.

5. A receptacle making machine comprising a shaft, hubs on the shaft, arms pivoted to the hubs, segments pivoted to the arms so as to be collapsible, and a detachable head at one end of the segments and spaced apart from said end to accommodate the head of the receptacle between said ends and the head.

6. A receptacle making machine comprising a shaft, hubs on the shaft, arms pivoted to the hubs, segments pivoted alongside of one another to the arms so as to be collapsible, the arms of alternate segments having knuckle joints, and means to hold the segments against collapsing.

7. A receptacle making machine comprising a shaft, a head mounted on said shaft, hubs on the shaft, arms pivoted to the hubs, segments seated at one end against the head and pivoted to the arms so as to be collapsible, the arms of alternate segments having knuckle joints, a second head at the opposite end of the segments provided with a centering pin, and a swinging arm having a

pivot engaging the centering pin to hold the second head toward the segments.

8. A receptacle making machine comprising a core, an oscillatory arm arranged to move lengthwise of the core, a roller on the arm to guide strip material to the core, means to feed a coating substance to said roller, and means to simultaneously turn the core and move the arm to wrap the strip material with abutting edges around the core first toward one end of the core and then toward the opposite end of the core.

9. A receptacle making machine comprising a core, an oscillatory arm arranged to move lengthwise of the core, a tank on said arm to hold a coating substance, a roller in the tank to distribute the coating substance to strip material, and means to simultaneously turn the core and oscillate the arm to wrap the coated strip material with abutting edges around the core first toward one end of the core and then toward the opposite end of the core.

10. A receptacle making machine comprising a core, a pivoted arm arranged to move lengthwise of the core, a roller mounted on the arm above the core to guide strip material to the core, a spool spindle mounted on the arm, and means to simultaneously turn the core and swing the arm to wrap the strip material with abutting edges around the core first toward one end of the core and then toward the opposite end of the core.

11. A receptacle making machine comprising a core, an oscillatory arm arranged to move lengthwise of the core, a roller to guide strips of material to the core, spools mounted on the arm in staggered relation, and means to simultaneously turn the core and oscillate the arm to wrap the strips of material with abutting edges around the core first toward one end of the core and then toward the opposite end of the core.

12. A receptacle making machine comprising a frame, a shaft journaled on the frame, a head mounted on the shaft, a core-body

formed of segments resting against said head, a second head, means to hold the second head toward the core-body, an oscillatory arm pivoted at one end to the frame and having its opposite end adjacent the core-body, and means operatively connecting said shaft to the oscillatory arm whereby the arm will swing a predetermined amount along the core to every revolution of said core.

13. A receptacle making machine comprising a frame, a core rotatably mounted on the frame, an arm pivoted to the frame to swing lengthwise of the core, means to turn the core and swing the arm, a strip-guiding head pivoted to said arm, stops on the arm at the sides of the head to limit the turning of the head on its pivot, and means brought into action by swinging of the arm to turn the head relative to the arm.

14. A receptacle making machine comprising a longitudinally curved core, a strip-feeding head adjacent the core, means to turn the core, and means operating in an arc to move the strip-feeding head in a curve corresponding to the longitudinal curvature of the core.

15. A receptacle making machine comprising a longitudinally curved core, a strip-feeding head reciprocably mounted adjacent the core, means to turn the core, means carrying said head and operating in an arc to move the strip-feeding head in a curve corresponding to the longitudinal curvature of the core, and means operating near the ends of the stroke of the head to turn the head in the opposite direction to the direction of travel of said head.

In testimony whereof, I have hereunto set my hand at Los Angeles, California, this 26th day of March, 1915.

ERNEST J. CROCKETT.
